UNITED STATES PATENT OFFICE.

WILLIAM L. PIERCE, OF NEW YORK, N. Y., ASSIGNOR OF ONE-FOURTH TO WILLIAM J. BELL, OF KINGS COUNTY, NEW YORK.

SEWING-MACHINE.

1,278,204.

Specification of Letters Patent. Patented Sept. 10, 1918.

Application filed April 25, 1914. Serial No. 834,291.

To all whom it may concern:

Be it known that I, WILLIAM L. PIERCE, a citizen of the United States, residing at the borough of Manhattan, in the county of New York and State of New York, have invented certain new and useful Improvements in Sewing-Machines, of which the following is a specification, reference being had therein to the accompanying drawing.

10 My invention relates to improvements in sewing machines, and more particularly has reference to what is generally understood as a blind stitching machine.

Referring to the accompanying drawings,

15 Figure 1 is the head of a sewing machine in side elevation, partly in cross section and partly broken away, illustrating one application of my invention. Fig. 2 is a cross section on the line 2—2 of Fig. 1. Fig. 3 is a

20 cross sectional end view on the line 3—3 of Fig. 1, and Fig. 4 is an end view looking from right to left at Fig. 1. Fig. 5 illustrates a sample of the sewing on a piece of goods, Fig. 6 is a cross section of the same

25 on an enlarged scale, and Figs. 7, 8, 9 and 10 illustrate modifications.

Referring now more particularly to Figs. 1 and 2, 7 is the driving shaft carrying the usual hand wheel 8 and belt and pulley 9

30 and 10 respectively. Upon this shaft it will be observed is mounted a pinion 11 which meshes with the pinions 12 and 13 upon the shafts 14 and 15 respectively. The shaft 14 it will be observed is provided with

35 an eccentric 16 which carries the lever 17 pivoted to the lever 18 as shown and which is mounted upon the bearing 19 and is resiliently retained by suitable means such as the spring 20, said lever having mounted at its

40 outward extremity a suitable sliding, lifting member or bender 21 provided with the chain 22, so that upon each two revolutions of the driving shaft 7, it will be observed the lifting member 21 is raised once upon

45 the bearing 19 against the action of the spring 20.

The driving shaft 7, it will be observed, also carries a pinion 23 which meshes with the pinion 24 upon the shaft 25, carrying the

50 hook 26, which hook it will be observed makes four revolutions with each movement of the lifting member 21.

At the end of the driving shaft 7 it will also be observed is provided the crank 27

55 carrying the connecting rod 28 pivotally

connected to the needle bar 29, at the opposite extremity of which is mounted the needle 30 by means of the bracket 31, and from which it will be seen, looking at Fig. 1, that the needle reciprocates horizontally while the lifting member 21 is moving.

The feeding wheels 32—32' are securely mounted upon the shaft 33 which it will be observed passes through the U-shaped support 34 which in turn it will be observed on looking at Fig. 3, engages the eccentric rod 35, by means of the pin 36 which it will be seen projects into the recess 37 of the U-shaped member. 38 and 39 are ratchet wheels securely mounted upon the shaft 33, 70 and 40 and 41 are pawls secured upon the eccentric rods 35—35'. These eccentric rods are mounted upon eccentrics 42 and 43 which in turn are secured to the driving shaft 7 so that the eccentric rods 35—35', it will be observed, are vertically reciprocated as the driving shaft 7 is rotated, and from this it will also be seen that the pawl 40 will engage the ratchet wheel 38 upon each return stroke of the eccentric rod 35 thereby intermittently rotating the shaft 33 and its feeder wheels 32—32'.

For the purpose of reversing the feed it will be seen that upon pulling downwardly upon the chain 44 attached to the rod 45 projecting from the U-shaped member 34, the same is drawn downwardly against the action of the spring 46, and the pin 36 is thereby forced leftwardly with its eccentric rod 35, thereby disengaging the pawl 40 from 90 the ratchet wheel 38 while at the same time the pin 47 within the cam rod 35' will slip into the recess 48 thereby causing the pawl 41 to engage the ratchet wheel 39 so that the rotations of the feeder wheels 32—32' are 95 thereby reversed.

The bar 49 it will be observed is pivotally mounted upon the ends of the studs 50—51 which are secured in the outer wall or frame 52 by any suitable means such as the nuts 53. 100

Referring again to Fig. 2, it will be observed that the shaft 54 carries the pinion 55 which meshes with the pinion 56 upon the shaft 15, provided with the gear 13, so that by now referring to Fig. 4, it will be 105 observed that upon each rotation of the shaft 54 the cam 55 mounted on the end thereof serves to oscillate the bracket 56 carrying the presser plate 57, the other end of which is secured upon the bracket 58, and 110

it will also be observed that the movement of the presser plate 57 is simultaneous with and in opposite direction to the movement of the lifting member 21. The presser plate 5 it will also be observed is provided with a suitable tongue or throat 59. 60 indicates a bridge located between the hook 26 and the presser plate 57.

In operation, the goods is introduced between the presser plate 57 and wheel feed 32-32' and the goods is raised by the bender 21 through the presser plate into position so that the needle passes through the goods as indicated in Fig. 6 by the reference character 61. This carries the thread of the needle through the goods and the same is engaged by the hook in the head and is locked with the other thread in the usual manner. The appearance of the exposed stitching is indicated to better advantage in Fig. 5 which is a view looking downwardly at Fig. 6.

It will be observed on reference to Fig. 1 that the shaft 33 is mounted in the adjustable bearing 32 which is resiliently projected upwardly by the coil spring 63. The screw 64 passes through the casing so as to depress the bearing of the lever 18 against the action of the spring 20 thereby lowering the bender or lifting member for the purpose of adjusting the position of the work. It will also be observed that by pulling down upon the chain 22, the bender or lifting member as well as the feeding wheels 32-32' can be dropped so as to sufficiently clear the foot or plate 57.

Referring now to Figs. 7 and 8 it will be observed that in this modification 70 indicates a needle guide mounted upon the shaft 71 which is so connected to the transmission 40 that as the shaft 71 is oscillated, the guide moves away from the needle on the return stroke of the needle before the eye of the needle reaches the edge thus preventing the edge of the guide from cutting the thread. 45 The plate 72 is preferably cut away at 73 to allow the goods to be pushed through by the bender 21 thus bringing the same properly within the path of the needle. From this it will be seen that the plate 57' 50 and the guide 70 move independently.

Referring now to Figs. 9 and 10 it will be observed that in this modification the feed shaft 33 is provided with a concentric outer shaft 33' said shafts being provided 55 with the pinions 38 and 39 respectively. Upon the opposite end of the shaft 33 is provided the gear 73 and upon the same end of the hollow shaft 33' the gear 74. These gears mesh with the smaller gears 75 and 76 respectively upon the shaft 77 which also carries the feed wheels 78 and 79 mounted oppositely as shown, suitable provision being made for the bender 21 to pass between. Thus it will be seen that when the U-shaped 65 member is operated either of the feeds 75

or 76 may be thrown into action and the direct or reverse action of the feed readily controlled.

Of course it will be understood that various modifications may be made without departing from the spirit of the invention as claimed.

I claim:

1. In a sewing machine, a drive shaft, a hook shaft carried at right angles to said drive shaft, both of said shafts being located in the same plane, a presser foot, a throat plate in combination therewith, a feeding wheel, a needle, and a bender, said foot being located above said wheel, needle and bender, and means in combination with said foot to allow said bender to elevate the material to be operated upon above the path of said needle means for intermittently operating said foot. 75

2. In a sewing machine, a drive shaft, a hook shaft at right angles to said drive shaft, both of said shafts being located in the same plane, a presser foot, a throat plate in combination therewith, a feeding wheel, a needle, and a bender, said foot being located above said wheel, needle and bender, and means in combination with said foot to allow said bender to elevate the material to be operated upon above the path of said needle, 90 said foot being hinged at the left side thereof and an eccentric at the right side of said foot adapted to operate the same once for each double operation of said needle. 95

3. In a sewing machine, a drive shaft, a hook shaft at right angles to said drive shaft, both of said shafts being located in the same plane, a presser foot, a throat plate in combination therewith, a feeding wheel, a needle, and a bender, said foot being located 100 above said wheel, needle and bender, and means in combination with said foot to allow said bender to elevate the material to be operated upon above the path of said needle, said foot being hinged at the left side thereof and an eccentric at the right side of said foot adapted to operate the same once for each double operation of said needle, 105 a ratchet driving device coöoperating with said foot, and means for reversing the action of 110 said ratchet driving device. 115

4. In a sewing machine, a drive shaft, a hook shaft disposed at right angles to said drive shaft, both of said shafts being located in the same plane, a presser foot, a throat plate in combination therewith, a feeding wheel, a needle and a bender, said foot being located above said wheel, needle and bender, and means in combination with said foot to allow said bender to elevate the material to be operated upon above the path of said needle, said foot being hinged at one side thereof and an eccentric at the other side of said foot adapted to operate the same once for each double operation of 120 125 130 135

said needle, a ratchet driving device and means for reversing the action of the same, means for moving said bender independently or in combination with said wheel, and a 5 movable needle guide adapted to move to or from the under side of said needle.

5. In a sewing machine, a drive shaft, a hook shaft, disposed at right angles to said drive shaft, said shafts being located in the 10 same plane, a pressure foot and a throat plate in combination therewith, a feeding wheel, a needle, and a bender, said foot being located above said wheel, needle and

bender, means in combination with said foot to allow said bender to elevate the material to be operated upon above the path of said needle, and a movable needle guide adapted to move to or from the under side of said needle. 15

In testimony whereof I hereunto affix my 20 signature in the presence of two witnesses.

WILLIAM L. PIERCE.
